UNITED STATES PATENT OFFICE

BICKNELL HALL, OF GLOUCESTER, MASSACHUSETTS

HANGING DOOR

Application filed December 19, 1929. Serial No. 415,205.

This invention relates to the hanging of doors, and a primary object of the invention is to provide a hinging means which may be mounted in the door joint so as to be concealed when the door is closed and which will serve to swing the door about an exterior axis. While adaptable to many uses, either in combination with other hinges of similar structure or otherwise, my invention finds a particular application to the hanging of automobile doors having the customary turn-under, and by way of illustration I will herein describe its application to such a use and in a combination which in itself embodies novel features.

My invention will be well understood by reference to the following description of an embodiment thereof shown by way of example in the accompanying drawings, where-

20 in:

Fig. 1 is a rear elevation of the body hinge pillar and door hinge pillar of an automobile body, the right hand or off pillar being shown, and with part of the door pillar broken away;

Fig. 2 is a section on a larger scale in the plane of the line 2—2 of Fig. 1 showing the door in open position. Parts are shown in this and the following sections which are

30 omitted in Fig. 1.

Fig. 3 is a similar view in the plane of the line 3—3;

Fig. 4 is a view similar to Fig. 3 showing the door in closed position;

35 Fig. 5 is an elevation of a hinge detached and in expanded or open position;

Fig. 6 is a perspective diagram; and

Fig. 7 is a sectional detail, showing in exaggerated manner a feature of construction.

40 Referring to the drawings, I have shown in Fig. 1 a body hinge pillar 7 of an automobile body, herein the cowl pillar, on which is hung the door hinge pillar 9 of a door provided with the customary overlap flange 11 (see Figs. 2 and 3). I have herein shown the door as hinged to swing on a center line or hinge axis which in the upper part of the body lies inwardly of the exterior surface thereof but which on account of the turn-45 under of the vehicle, which exists because

such a body is narrower at the sills than at the belt, lies exteriorly of said outer surface at the lower part of the body, as illustrated in Fig. 1. I have herein shown the top hinge 13 and central or belt hinge 15 as being of a type devised by Frederick J. Kubler, of New York city, and embodying (see Fig. 2) a leaf 15 secured to the door pillar 9 and a cooperating leaf 17 secured to the body pillar 7 and having its proximal portion offset into the plane of leaf 15 providing a neck 19 into which the overlap flange 11 turns in the opening movement of the door, the body pillar being suitably recessed as shown to pass the flange 11 in its turning movement. The center line defined by these hinges is inward of the exterior surface of the door.

55 In accordance with my invention I provide a hinge for the lower part of the door at the location of the turn-under which may be received in the door joint and thus concealed when the door is closed but which has an inherent law of motion about the same center line as the upper hinges, that is, a center line exterior to the hinge and to the body, so that the lower portion of the door is supported and guided in its swinging movement apart from the support and guide provided by the upper hinges.

60 In the embodiment of my invention shown, for reasons of constructional simplicity the hinge for the lower portion of the door is symmetrical about central vertical and horizontal planes although it will be apparent when the present description is concluded that such construction is not necessary. Herein (see Fig. 5) the hinging means is organized as a unitary structure or "hinge" and comprises two attaching plates 21 and 23 similar to ordinary hinge butts which may be secured by screws or other means to the body pillar and door pillar respectively and which support and are connected by a pair of oppositely disposed toggles. Herein an upper toggle comprises links or arms 25 and 27 hinged to plates 21 and 23 along oblique axes 29 and 31 respectively and pivoted together on an oblique axis 33. As shown in Fig. 1, the axes converge in such manner that if prolonged they would intersect a horizontal line

drawn through a point P in the center line of the upper hinges, which is also the center of motion of the hinge about to be described. The second toggle embodying arms 35 and 5 37 has the oblique axes 39 and 41 by which it is connected to the jamb and door and its links or arms are connected by pivot 43. These links likewise converge to a point, in the center line as indicated in Fig. 1, but are 10 oppositely arranged to the pivots of the other toggle in such manner that the elements of at least one pair of corresponding pivots of the two toggles are relatively transverse. I have herein shown the two toggles as of similar 15 dimensions and the arms in each toggle as of equal length and the pairs of pivots 29—31 and 39—41 closing in opposition to each other (see Fig. 4) and lying parallel one to another in closed position, although other 20 constructions may be adopted. This, however, eliminates troublesome angles and permits the links to be counterparts one of another. The links or arms of the toggles are made of suitable shape and dimension to be 25 housed in the door joint, as illustrated in Fig. 1, and their opposed edges 45 and 47 are formed at such an angle as to permit the door to move to open position, at which time these edges approach one another toward the position 30 shown in Fig. 5.

Having thus described in a general way the physical elements of the particular embodiment of the invention illustrated, the principles embodied therein will be readily 35 understood by reference to the diagram of Fig. 6. Referring to that diagram, I have there shown three pivotal axes DG, EH and FJ disposed to converge at a point P. The axes DG and FJ each constitute an element 40 of a cone whose apex is at P, and they may be of equal inclination forming elements of one cone whose base is M as shown. If the toggle formed by joining these axes is permitted to expand and collapse, the axes always 45 intersect whatever the positions of the parts. Thus if DG is fixed, FJ may roll around the cone, revolving about the point P. The inclination of EH will vary but it will still gyrate about P. The relative movement 50 of the pivots and that which would be effected if the hinge detached were collapsed and opened in the hands is a gyratory movement of all three, all revolving about P. Thus a door mounted on FJ could move in 55 a circle about the center line CP. Movement of the axis FJ in the surface of the vertical right cone shown in the diagram, however, presupposes that all the three pivots partake of the hinging movement and that it is not 60 concentrated in any one of them, for obviously any one or two of the pivots could be held without preventing turning of the other. The proper movement may be effected and the door efficiently supported by 65 utilizing an adjacent oppositely disposed

toggle whose pivots operate in a cone or cones having the same axis but upside down with respect to the cone shown in the diagram (Fig. 6). The movement of one toggle tending to displace the point P from the vertical center line shown is balanced and resisted by the action of the other toggle, the tendency of which is to act in the other direction. Thus the parts corresponding to the pivots FJ will roll about a vertical cone 70 and the door attached thereto will swing about the vertical center line CP.

I have herein described and shown, more particularly in Fig. 4, pivots 29 and 31 which are disposed parallel to one another in the closed position of the hinge and which hence do not intersect at a point in the center line. Their position corresponds to the lines DK and FL in the diagram which when produced are tangent at Q and R respectively to a circle about the point P, the diameter of which is equal to the distance between the centers of pivots 29 and 31 in the closed position of the door in Fig. 4. The plane PRCF coincides with the plane PCF since 80 they have the lines PC and CF in common, and the door carried by the pivot FL (and the corresponding oppositely arranged pivot) will swing about the center line as 85 in the case of the inclined pivot FJ. As the door opens, the line FR gyrates about the center line CP, always tangent to the circle whose center is at P, as will be clear from Fig. 4, and thus revolving about the point P although at a fixed distance therefrom. The links DKHE and FLHE correspond to 90 the links 25 and 27 respectively of the hinge shown, and Fig. 6 provides a diagram of the upper toggle of the hinge illustrated in the other figures.

The inclination of the various pivots of the toggles may widely vary but are conformed as nearly as possible to the vertical rather than to the horizontal in order to support the door against sagging movement. The form and shape of the links may likewise be varied as structural convenience may dictate and to accommodate them to the shape and dimensions of the door joint in which they are housed. I prefer, however, 100 links as short as possible to provide the desired and necessary range of movement for the door so that the door in its open position is supported by as short an arm as conveniently may be. The pivotal joints are 105 preferably formed with three knuckles (see Fig. 7), a central knuckle, as 49, on one part being received between lateral knuckles, as 51, on the other and the pintle, as 33, has a binding fit in the central knuckle 49 and a turning fit in the lateral knuckles. The looseness in the latter is, of course, enormously exaggerated in Fig. 7. One link thus turns on the other as on trunnions, and the bearing 110 surface of the pivotal joint is as wide as 115

the links permit. This contributes to the rigidity of support and accuracy of movement afforded by the hinge as a whole.

The edges 45 and 47 of the opposed toggles 5 may be arranged as shown in the drawings so that they approach each other in the expanding movement of the toggles, and they are preferably made to contact one with another, as illustrated in Fig. 5, to limit the 10 swinging movement of the door and mutually to prevent one another from coming to dead center. The angle of the toggles in their open position, as shown in Fig. 3, may provide for receiving the overlap flange 11 15 of the door in its open position as shown. The hinge constructed in this manner forms an efficient and rugged door stop.

I am aware that the invention may be embodied in other specific forms without departing from the spirit or essential attributes thereof, and I therefore desire the present embodiment to be considered in all respects as illustrative and not restrictive; reference being had to the appended claims 25 rather than to the foregoing description to indicate the scope of the invention.

I claim:

1. Means for hinging a closure to swing about an exterior axis comprising a pair of 30 adjacent toggles, each toggle having a central pivot which produced intersects said axis and terminal pivots which revolve about said intersection, said toggles being oppositely arranged.

2. Means for hinging a closure to swing about an exterior axis comprising a pair of adjacent toggles, each toggle having a central pivot which produced intersects said axis and terminal pivots which revolve about said intersection, all said pivots being oblique to said axis at angles less than 45°, said toggles being oppositely arranged.

3. Means for hinging a closure to swing about an exterior axis comprising a pair of adjacent toggles, each toggle having a central pivot which produced intersects said axis and terminal pivots which revolve about said intersection, said toggles being oppositely arranged and when expanded contacting one with another to limit opening movement of the door.

4. Means for hinging a closure to swing about an exterior axis comprising two toggles having pivots oblique to said axis and converging for gyratory movement thereabout, a pair of corresponding pivots in the two toggles being mutually transverse one to the other, the axes of the pivots intersecting in a plane between said toggles.

5. Means for hinging a closure to swing about an exterior axis comprising two toggles received in the door joint and having corresponding axes mutually transverse to support and direct the closure in its swinging movement, said toggles in their expand-

ing movement contacting to prevent their reaching dead center and to check the swinging movement of the closure.

6. Means for hinging a closure to swing about an exterior axis comprising two toggles, each having pivots converging toward said axis for gyratory movement thereabout, a pair of corresponding pivots in the two toggles extending obliquely to said axis at opposite inclinations transverse one to the other. 70

7. Means for hinging a closure to swing about an exterior axis comprising two oppositely arranged toggles received in the door joint and each having its pivots disposed obliquely to said axis and converging for gyratory movement about a point therein. 80

8. Means for controlling swinging movement of a closure comprising a pair of adjacent oppositely arranged toggles, each toggle having its pivots converging for gyratory movement about a point in the axis of swinging movement, said toggles when expanded mutually contacting one with another to limit the swinging movement. 85

9. In a concealed hinge, two pairs of links, the links of each pair being pivoted to each other and respectively to jamb and hinge style, the axes of said pairs being relatively angularly disposed to support the closure 90 and to enforce swinging movement thereof about an exterior axis, said pairs in the opened or expanded position thereof mutually engaging one another to provide a stop and mutually preventing one another from reaching dead center. 100

In testimony whereof, I have signed my name to this specification.

BICKNELL HALL.
